UNITED STATES PATENT OFFICE.

JOHN MURRAY, OF LONDON, ENGLAND.

BOOKBINDER'S PRESS.

Application filed March 15, 1922. Serial No. 543,925.

To all whom it may concern:

Be it known that I, JOHN MURRAY, a subject of the King of Great Britain and Ireland, and a resident of London, England, 5 have invented certain new and useful Improved Bookbinders' Presses, of which the following is the specification.

The invention relates to hand operated bookbinders' presses of the kind in which a 10 fixed head coacts with a movable platen on a table adapted to receive the material to be pressed and in which there are means for rapidly bringing the platen up to the material to be pressed which is arranged 15 against the head and for thereupon advancing the platen slowly and with pressure, there being means for releasing and rapidly returning the platen.

The invention has for its object to provide 20 improved means for operating the head in the manner set forth, which means provide a train of positive gearing which is automatically brought into action for the pressing operation.

25 In carrying out the invention, there is supported in front of the fixed head, a face plate. The face plate is so mounted on springs that while it normally lies a short distance in front of the fixed head, pressure 30 put upon it causes it to retire toward the latter.

The platen is carried in guides on the table and is operated by a simple upstanding handle for the rapid advancing and retiring motion, and by a rack bar fixed to it and operated by a handwheel through gearing on a transverse shaft for the slow and pressure applying motion. This gearing which is 35 preferably of epicyclic form is thrown into and out of operative connection with the rack bar by shifting mechanism operated by a rod or the like connected to the spring-supported face plate.

40 In the drawings, Fig. 1 is a side elevation of one example of a press made in accordance with my invention;

Fig. 2 is a side elevation;

Fig. 3 is a plan view;

Fig. 4 is a sectional plan view on an enlarged scale of part of the press; and

Fig. 5 is an elevation on an enlarged scale showing the ratchet, pawl and operating link.

55 In this example, there is at one end of the table A a fixed head B. In front of this

fixed head there is supported on the table a face plate C which is resiliently maintained at a short distance in front of the head by a spring D arranged in a cavity in the head and engaging a plunger E on the back of the 60 face plate. A stud F is provided for adjusting the position of the plate.

The platen G is carried in guides H on the table A and is operated by hand by a simple upstanding handle J for the rapid 65 advancing and retiring motion.

For the slow and pressure-applying motion, it is operated by a rack bar K fixed to it and operated by a pinion L on a sleeve M on a transverse shaft N through the well 70 known epicyclic gearing from a handle P on the shaft N. As is more clearly seen in Figure 4, this gearing consists of a series of pairs of planetary pinions R, S mounted in any suitable manner in the central web 75 of a casing Y fixed to the shaft N and gearing on the one hand with a pinion V₁ to which is attached a ratchet wheel A₁ and on the other with a pinion V₂ which is fixed to the sleeve M having on it the pinion L which 80 meshes with the rack K.

Below the ratchet wheel A₁ are vertical guides Z guiding pawl B' which is adapted to engage the ratchet wheel when pushed upwards by a pin P₂ fixed to the pawl B₁, 85 and sliding in an inclined slot T₁ in a horizontally guided link T. This link T is attached to the end of a tappet C₁ connected to the face plate C. The pawl B₁ is thus operated from the face plate by means of the 90 slot T₁ raising or lowering the pin P₂. The horizontal movement of the rod C₁ then produces the vertical movement of the pawl B₁ which is necessary to make it engage with the ratchet wheel A₁. This 95 rod C₁ passes through the face plate, is provided with a collar D₁ there against and with a buffer spring E₁ arranged between the face plate and a collar G₁ on the end of the rod. A handled lever H₁, pivoted on the 100 table and engaging between collars J₁ on the rod C₁ is provided for operating the latter independently of the movement of the face plate.

When the shaft N is rotated by the handle 105 P, the casing Y revolves and carries the planetary wheels R, S around the pinions V₁ and V₂. If the pawl B₁ is in engagement with the ratchet wheel A₁, the pinion V₁ cannot revolve and the motion due to 110

the gear ratio will be transmitted to the pinion V_2 and pinion L, and so to the rack K and sliding platen G.

When the pawl B_1 is out of engagement with the ratchet wheel A_1 the wheel V_1 is free to rotate and any motion from the rack K simply causes the wheel V_1 to turn idly.

In operation, the material to be pressed is placed on the table B and against the spring controlled face plate C. When sufficient material has been so placed, the movable platen G is run rapidly forward by the handle J so that its impact upon the material causes the face plate to retire. Meantime the pawl B_1 has been out of engagement with the ratchet wheel A_1 on the epicyclic train, so that the platen may be moved rapidly forward. But immediately the face plate is retired, it causes the tappet rod C_1 connected to it to operate the pawl and lock the epicyclic train. The material, partially compressed by the initial blow, is further compressed by operation of the now interlocked epicyclic train by the handle P. When compression is complete, the pawl is withdrawn by a movement of the tappet rod, freeing the epicyclic train, and the movable platen may then be freely and rapidly withdrawn for removal of the material.

What I claim is:—

1. In a hand-operated bookbinder's press, having a fixed head and a movable platen, means permitting rapid advancement of the platen and alternative means for advancing the platen slowly in combination with means controlled by the pressure between the platen

and the head for automatically shifting from one advancing means to the other.

2. In a hand-operated bookbinder's press, having a fixed head and a movable platen, means permitting rapid advancement of the platen and alternative means for advancing the platen slowly in combination with means controlled by the pressure between the platen and the head for automatically shifting from one advancing means to the other, said shifting means having a face plate spring-supported from the head and operatively connected to the advancing means. 45 50

3. In a hand-operated bookbinder's press, a fixed head and a movable platen, means permitting rapid advancement of the platen and gearing for advancing the platen slowly in combination with guides in which said platen slides freely and alternative means for locking said platen to said slow gearing. 55

4. In a hand-operated bookbinder's press, having a fixed head and a movable platen, means permitting rapid advancement of the platen and alternative means for advancing the platen slowly in combination with means controlled by the pressure between the platen and the head for automatically shifting from one advancing means to the other, 60 65 said shifting means having a face plate spring-supported from the head, an epicyclic train, a pawl controlling said train and a tappet rod connecting said pawl to said face plate, substantially as described. 70

In testimony whereof I have signed my name to this specification.

JOHN MURRAY.
